(57) **ABSTRACT**

A suspended mirror system and a method of suspending a mirror. The mirror system has: a frame; a convex reflective surface on the frame; and a support system connecting between a mounting base and the frame and configured so that the frame is suspended in an operative position below a part of the mounting base. The support system has at least one elongate flexible component in a depending relationship with the part of the mounting base and under tension from a weight of the frame.

SYSTEM FOR AND METHOD OF SUSPENDING A MIRROR

BACKGROUND OF THE INVENTION

Field of the Invention

This invention relates to mirrors, such as convex mirrors, and, more particularly, to a system for, and method of, suspending a mirror in an operative position.

Background Art

Mirrors are used worldwide in many different environments to allow persons to observe areas that are not in direct line of sight. There are many reasons that mirrors are used, prime among those being safety as persons on foot and in/on vehicles maneuver in shared and intersecting routes.

As one example, manufacturing and product handling facilities commonly use strategically placed convex mirrors to eliminate blind spots at locations where it is anticipated that persons and/or vehicles will converge. A typical floor layout in these facilities will have aisles throughout designed to accommodate traffic patterns for persons walking and/or operating vehicles as they perform coordinated tasks. In large facilities, persons may share and cross routes with many others walking and operating vehicles used during manufacturing processes, while transporting completed products, etc. These regular flow patterns are coordinated also with workers, as they enter and leave individual work spaces, and supervisors that move throughout facilities.

With a large footprint, there may be a relatively complex network of travel routes that are identifiable by floor markings, shelves, walls, etc. In most facilities, these routes intersect in such a manner that care must be taken to avoid collisions. While persons are generally trained to exercise caution while navigating shared spaces, particularly at blind intersections, mirrors are commonly incorporated, recognizing that persons are often moving while distracted or while otherwise not giving full attention to identifying the presence of other persons and/or vehicles.

It is common in such facilities to see convex mirrors mounted to vertically extending surfaces, such as on fixed walls, shelving, etc. In many facilities, there may be adequate vertical mounting surfaces to which mirrors can be fixedly mounted.

Commonly, multiple mounting arms are connected between a fixed vertical support and a frame on the mirror. The mounting structure can be configured to adjustably place the convex mirror so as to optimize the usable horizontal and vertical reflective image ranges. While a convex mirror technically has the ability to reflect images over wide horizontal and vertical ranges, the mirrors are commonly strategically aligned, recognizing that only portions of the reflected horizontal and vertical ranges are large enough to be practically usable—these usable ranges being in areas closer to the center of the convex shape.

In some facilities, some, if not all, of the “critical intersections” do not have rigid structures usable to mount such safety mirrors. Operators of businesses in this category generally have two options. First, they can proceed without using mirrors and highlight critical locations as by lights, such as flashing lights or strobes, by using floor markings, etc. While these steps may reduce risk, they are effective only if persons exercise an appropriate level of care—generally requiring that persons slow down when approaching, or stop when at, a blind intersection.

2

Alternatively, dedicated supports may be provided for the mirrors. Typically, these dedicated supports will be in the form of a rigid base to which the mirror can be fixedly mounted. If the base is incorporated at floor level, it may provide an obstruction to workers and may interfere with traffic flow patterns. Generally, any structure added within a facility competes for usable space, which is almost always at a premium.

As noted above, in the absence of any structure for readily mounting safety mirrors, operators of such facilities have often opted to not use mirrors at different locations where they would be beneficial. These decisions are often made in the interest of controlling costs, as a result of which movements of personnel around a space may be disrupted, and in a worst case injuries may result.

The industry continues to seek out affordable and practical ways to facilitate safe and coordinated movement of personnel, on foot and in vehicles, in environments in which they navigate.

SUMMARY OF THE INVENTION

In one form, the invention is directed to a suspended mirror system including: a frame; a reflective surface on the frame; an intermediate support; a primary support configured to be connected to a mounting base so as to be in a mounting orientation wherein the primary support extends downward from a part of the mounting base and is connected to the intermediate support; at least one rigid component connecting between the frame and the intermediate support; and at least one holding component connecting between the frame and at least one of the at least one rigid component, the primary support, and the intermediate support to stabilize the frame with the frame in a desired angular relationship with the intermediate support. The frame, intermediate support, and at least one rigid component are configured so that with the primary support in the mounting orientation, an angular relationship between the frame and intermediate support can be controllably changed so as to change and maintain an angular orientation of the reflective surface to thereby allow selection of a vertically reflecting image range for the reflective surface.

In one form, the reflective surface has a convex shape.

In one form, the frame is made up of a substantially flat panel.

In one form, the primary support has first and second components that with the primary support in the mounting orientation connect to the intermediate support at spaced locations.

In one form, the primary support has first and second components that with the primary support in the mounting orientation connect to the mounting base at spaced locations.

In one form, the intermediate support is in the form of an elongate bar with a length that extends substantially horizontally with the primary support in the mounting orientation.

In one form, the frame is made up of a substantially flat panel. The at least one rigid component connects between the substantially flat panel and the elongate bar.

In one form, the at least one rigid component is connected to at least one of the substantially flat panel and the elongate bar for guided pivoting movement relative to the at least one of the substantially flat panel and the elongate bar.

In one form, the at least one rigid component has a length and is configured so that the length of the at least one rigid component can be changed.

In one form, the reflective surface is defined on a body having a cup shape with an open end. The substantially flat panel is at or adjacent the open end.

In one form, the at least one rigid component consists of first and second rigid components.

In one form, the first and second rigid components are each connected to at least one of the frame and intermediate support for guided pivoting movement relative to the at least one of the frame and intermediate support around a shared axis.

In one form, the at least one holding component is in the form of a flexible elongate component with a length that connects between the frame and intermediate support. The flexible component is configured so that an effective length of the flexible component between the frame and intermediate support can be selectively changed.

In one form, the primary support in the mounting orientation has a length and is made up of a flexible component and is configured so that an effective length of the primary support can be selectively changed.

In one form, the invention is directed to a suspended mirror system including: a frame; a convex reflective surface on the frame; and a support system connecting between a mounting base and the frame and configured so that the frame is suspended in an operative position below a part of the mounting base. The support system has at least one elongate flexible component in depending relationship with a part of the mounting base and under tension from a weight of the frame.

In one form, the support system has first and second elongate flexible components each in depending relationship with the part of the mounting base and under tension from a weight of the frame.

In one form, the at least one elongate flexible component makes up a primary support on the support system. The support system further includes an intermediate support between the frame and the primary support. The frame is configured to be controllably angularly reoriented relative to the intermediate support so as to change and maintain an angular orientation of the reflective surface to thereby change a vertically reflecting image range for the reflective surface.

In one form, the mirror system has a body with a cup shape with a convex surface on which the reflective surface is located.

In one form, the invention is directed to a method of suspending a mirror including the steps of: obtaining a body with a convex surface on which a reflective surface is defined, the body connected to a frame; suspending the frame from a mounting base using at least one flexible component between the mounting base and frame such that the at least one flexible component: a) depends from a part of the mounting base; b) suspends the frame in an operative position below the part of the mounting base; c) is under tension from a weight of the frame; and d) provides a sole weight support for the frame. With the frame in the operative position, the reflective surface reflects images in a vertically reflecting image range.

In one form, the method further includes the step of changing an orientation of the frame to thereby change the vertically reflecting image range.

BRIEF DESCRIPTION OF THE DRAWINGS

FIG. 1 is a schematic representation of a mirror of the type that can be used with the present invention:

FIG. 2 is a schematic representation of a system, according to the invention, for suspending a mirror from a mounting base;

FIG. 3 is a schematic representation of the inventive system, as in FIG. 2, and showing additional optional details of the system;

FIG. 4 is a front elevation view of one exemplary form of system as shown in FIGS. 2 and 3;

FIG. 5 is a rear perspective view of the system in FIG. 4;

FIG. 6 is a cross-sectional view of an intermediate support on the system taken along line 6-6 of FIG. 5;

FIG. 7 is an enlarged elevation view of a connector usable between components on the system in FIGS. 4 and 5;

FIG. 8 is a partially schematic representation of an exemplary connector between a mounting base and a support system on the inventive system;

FIG. 9 is a fragmentary, side elevation view of one component on a connecting structure cooperating between the mirror and the intermediate support on the system in FIGS. 4 and 5;

FIG. 10 is an enlarged, fragmentary view of one of the connections between components in FIG. 9;

FIG. 11 is a schematic representation of the inventive system in an initial setup stage;

FIG. 12 is a view as in FIG. 11 wherein a mirror on the system has been adjusted to a selected operative position/orientation;

FIG. 13 is a schematic representation of a connection between a holding component and separate parts of the system to maintain a selected angular orientation for the mirror; and

FIG. 14 is a flow diagram representation of a method of suspending a mirror, according to the present invention.

DETAILED DESCRIPTION OF THE PREFERRED EMBODIMENT

The invention is directed to a suspended mirror system without limitation as to its particular environment. A mirror, as contemplated by the invention, and shown schematically at 10 in FIG. 1, is any structure consisting of a body 12 having an exposed reflective surface 14. While not so limited, the invention is particularly suitable for, and described hereinbelow with respect to, a mirror 10 with a convex reflective surface 14. As depicted, the body 12 has a cup shape on one side of which the reflective surface 14 is present.

The precise manner in which the mirror 10 is constructed is not critical to the present invention. For example, the reflective surface 14 may be integrally formed with the body 12 as a single layer or as one of multiple layers. Alternatively, the reflective surface 14 can be separately applied to the pre-formed body 12.

The suspended mirror system, as shown schematically at 16 in FIG. 2, consists of a frame 18, on which the reflective surface 14 is supported, and a support system 20 connecting between a mounting base 22 and the frame 18 and configured so that the frame and reflective surface 14 are each suspended in an operative position below at least a part of the mounting base 22.

The support system 20 has at least one flexible component 24 that is in depending relationship with a part of the mounting base 22 and under tension from the weight of the frame 18.

In one preferred form, there are at least first and second flexible components 24 that are arranged to cooperate between the mounting base 22 and frame 18 so that the

frame, while movable relative to the mounting base, is maintainable substantially in a single operative position/ orientation—confined against turning principally around a vertical axis.

As shown in FIG. 3, in one form, the at least one flexible component 24 makes up at least part of a primary support 26 on the support system 20. The support system 20 further includes an intermediate support 28 between the frame 18 and primary support 26. The intermediate support 28, which is optional within the broader concept of FIG. 2, is joined to the frame 18, through connecting structure 30. The connecting structure 30 allows the frame 18 to be controllably angularly reoriented relative to the intermediate support 28 so as to change an angular orientation of the reflective surface 14 on the frame 18 to thereby change a vertically reflecting image range for the reflective surface 14.

One exemplary form of the system, as shown generically in FIGS. 2 and 3, is shown in details in FIGS. 3-13. The exemplary form in FIGS. 3-13 is not intended to be limiting, as the generic showings in FIGS. 2 and 3 are intended to encompass virtually an unlimited number of different forms of each of the components therein and their interactions.

In this embodiment, the body 12 is cup shaped with an open end 32. The body 12 has an outturned annular flange 34 at the open end 32 which defines a support for the frame 18, shown in the form of a substantially flat panel. The frame/flat panel 18 is connected to the body 12 at the flange 34. The connection may be at or adjacent to the open end 32.

The intermediate support 28 is in the form of an elongate, rigid bar with a length L that extends substantially horizontally with the primary support 26 in the mounting orientation of FIGS. 4 and 5 and the frame 18 in its operative position—connected to the intermediate support 28 through the connecting structure 30 as shown in FIGS. 4 and 5. The flat shape of the bar is selected to facilitate attachment of various connectors thereto. The rolled, parallel edges add rigidity. The intermediate support 28 may take many very different forms and still perform the functions described herein.

The primary support 26 consists of at least one flexible component 24a with a length indicated by the double-headed arrow 36 between a part of the mounting base 22 and the intermediate support 28. In the depicted form, the flexible component 24 is a chain with interlocked links 38a. It should be understood that the flexible component 24a is not required to be flexible along its entire length. In the depicted form, the chain configuration extends fully between the mounting base 22 and the intermediate support 28.

In the depicted form, one end 40a of the flexible component 24a is connected to the intermediate support 28 by directing a free end part 42a through an opening 44a in the intermediate support 28 to cause a part of the free end 40a to wrap around a portion 46a of the intermediate support 28. The portion 46a on the intermediate support 28 is thus supported by an upwardly opening U-shaped seat 48a at the end 40a. The seat 48a may be formed by one of the links 38a or by a separate component, such as on an S-hook as shown at 50a in FIG. 7. The lower portion of the "S" defines the seat 48a, whereas the upper portion of the "S" defines an oppositely opening, curved seat 52a, as to engage one of the links 38a.

The S-hook 50a may be deformed after assembly to provide closed loops surrounding the intermediate support portion 46a and a link 38a on the flexible component 24a. This is, of course, only one of many different connecting arrangements that might be utilized.

The opposite/upper end 54a of the flexible component 24a can be connected to the mounting base 22 in any

suitable manner. As just one example, as shown in FIG. 8, a supporting hook 56a may be provided on the mounting base 22 to engage one of the links 38a, an S-hook, such as the S-hook 50a in FIG. 7, or another suitable structure.

It should be understood that the flexible component 24a may be permanently connected to each of the intermediate support 28 and mounting base 22 or releasably, as by not deforming/crimping components, such as the S-hook 50a, once its ends are engaged with the system 16.

With the chain arrangement shown, the effective length of the flexible component 24a can be easily changed by either cutting the same or engaging different lengthwise portions thereof with the mounting base 22 and/or intermediate support 28.

The elongate flexible component 24a may be joined in similar fashion directly between the mounting base 22 and frame 18, in the event that the intermediate support 28 and connecting structure 30 are not utilized.

In the depicted form, two additional elongate flexible components 24b, 24c are utilized. In the exemplary form, each of the flexible components 24a, 24b, 24c is the same and connects between the mounting base 22 and intermediate support 28 in the same fashion, though this is not a requirement. The flexible components 24b, 24c are connected adjacent opposite lengthwise ends of the intermediate support 28 with the flexible component 24a midway therebetween.

The multiple flexible component construction confines twisting of the intermediate support 28 around a vertical axis 30 relative to the mounting base 22. Thus, a consistent mounting orientation can be maintained for the primary support 26. A single flexible component, or two, or more than three, flexible components 24 might be utilized.

In the depicted form, the lengths of the flexible components 24 are substantially parallel over their full vertical lengths, though this is not a requirement.

The connecting structure 30 consists of at least one rigid component 58a connecting between the frame 18 and the intermediate support 28. In this embodiment, the rigid component 58a is made up of telescopingly engaged parts 60a, 62a that cooperatively produce an overall length L1 between opposite ends 64a, 66a.

In this embodiment, a mounting post 68a is fixed on the frame/flat panel 18, with a separate mounting post 70a fixed on the intermediate support 28. The mounting posts 68a, 70a project in cantilever fashion from the frame/flat panel 18 and the intermediate support 28 and define mounting seats 72a, 74a, respectively for pivot posts 76a, 78a. The post 76a guides pivoting movement of the end 66a relative to the post 68a around an axis 80a. The post 78a similarly guides pivoting movement of the end 64a relative to the post 78a around an axis 82a.

In the depicted form, the axes 80a, 82a are substantially parallel and horizontal with the mirror 10 in its operative position as in FIGS. 4 and 5.

In this embodiment, the connecting structure 30 consists of the rigid component 58a and a like, second, rigid component 58b which, while not required, is shown to have the same construction as the rigid component 58a and is connected to the frame/flat panel 18 and intermediate support 28 in like fashion. The additional rigid component 58 is desired to provide a stronger and more stable mount for the frame 18.

In one exemplary form, the connections between the ends 64a, 66a and the respective mounting posts 68a, 78a are the same, though this is not a requirement. As shown in FIG. 10, the exemplary pivot post 76a is defined by a bolt 84a which

is directed through the mounting post **68a** and the part **60a** on the rigid component **58a** to define the pivot axis **80a**. A threaded shank **86a** on the bolt **84a** accepts a nut **88a**. With the nut **88a** loosened, the part **60a** is free to pivot about the axis **80a** relative to the mounting post **68a**.

By tightening the nut **88a**, a relative angular position of the part **60a** and mounting post **68a** can be fixed. Lock washers **90** may be used to provide more positive fastening.

As noted above, the pivot connection at both ends **64a**, **66a** can be established using the same structure, which is also usable, but not required, in connecting the rigid component **58b**.

As depicted, the components **58a**, **58b** have ends that pivot around axes shared by the rigid components **58a**, **58b**.

In FIG. 11, a schematic representation is shown of the components described above to make up the system **16**, with the primary support **26** connected to the mounting base **22** and in a mounting orientation, wherein the flexible components **24** extend downward from the mounting base and are connected to the intermediate support **28**. The intermediate support **28** is in turn connected to the frame/flat panel **18** on the mirror **10** through the rigid components **58** on the connecting structure **30**.

The precise orientations of all the components between the mounting base **22** and the mirror **10** in FIG. 11 are dictated by their dimensions, weight, and points of connection. As depicted, the flexible component(s) **24** is/are put under tension by the weight of the mirror **10** suspended therefrom. The weight of the mirror **10** also pivots the rigid component(s) **58** on the connecting structure **30** so that the length of each connecting component **58** is substantially vertically aligned.

The mounting post **68a** is diametrically off-center so that the mirror **10** pivots under its own weight around the axis **80a** in the direction of the arrow **92**, generally to the operative orientation as shown in FIG. 11.

The frame **18**, intermediate support **28**, and at least one rigid component **58** are configured so that with the primary support **26** in the mounting orientation, an angular relationship between the frame **18** and intermediate support **28** can be controllably changed so as to change and maintain an angular orientation of the reflective surface **14** to thereby selectively change a vertically reflecting image range for the reflective surface **14**. The angular orientation of the intermediate support **28** around its length may actually change somewhat as the mirror **10** is pivoted and its weight is distributed differently—however, this pivoting movement will be treated herein as negligible.

At setup, the mirror **10** may be allowed to pivot under its weight to the FIG. 11 position. Alternatively, this pivoting movement can be confined by at least one holding component, shown schematically at **94** in FIG. 11, that is part of the connecting structure **30** and connects between the frame **18** and at least one of the at least one rigid component **58**, the primary support **26**, and the intermediate support **28**, to stabilize the frame **18** with the frame in a desired angular relationship with the intermediate support **28**.

In the depicted form, the at least one holding component **94** is a flexible component, in this embodiment in the form of a chain with links **96** making up part or all of its length. The holding component **94** in this form cooperates between connectors **98**, **100**, respectively on the frame **18** and intermediate support **28** and making up part of the connecting structure **30**.

Starting with the system **16** in the FIG. 11 state, the mirror **10** can be pivoted around the axis **80a** in the direction of the arrow **102**, generally to the FIG. 12 position. Depending

upon the degree of pivoting around the axis **80a**, the vertically reflecting image range is effectively changed. As noted previously, only a portion of the reflected image on the reflective surface is discernible adequately to be practically usable for its intended purpose. The desired angular position of the mirror **10**, determined by the angular relationship between the frame **18** and the intermediate support **28**, is maintained by engaging the at least one holding component **94** between the connectors **98**, **100**.

As shown in FIG. 13, connectors **104**, **106**, on the holding component **94**, and respectively cooperating with the connector **98** and connector **100**, may take an unlimited number of different forms, which are encompassed by the generic showing in FIG. 13.

For example, with the holding component **94** in the form of the chain shown, each of the links **96** may function as a connector. For example, the connector **100** may have a hooked arrangement such as an S-hook to engage a link **96**. The connector **98** may have a like configuration. The holding component **94** might be fixedly connected to one of the connectors **98**, **100**, and releasably connected to the other to allow for effective length adjustment of the holding element **94** and thereby selection of a different angular relationship of the mirror **10** relative to the support system **20** and components thereon. Alternatively, all connectors may be releasably engageable to facilitate selection and maintenance of different angular positions of the mirror **10**.

With the basic concepts described above, virtually an unlimited number of variations can be made as to allow different relative movement between the components, different angular relationships of the mirror **10**, different positions of the mirror **10** relative to other components, etc.

For example, the length **L1** of the rigid component **58a** may be changed by loosening a fastener **108** and relatively translating the telescopingly engaged parts **60a**, **62a**. When a desired length **L1** is established, the fastener **108** can be tightened to maintain the selected length **L1**. As seen in FIG. 11, the length of the component **58** dictates the arcuate path of the mirror **10** as it is pivoted from the FIG. 11 position towards or past the FIG. 12 position.

The suspension mounting of the mirror **10** allows for the mirror **10** to be strategically placed and oriented with solely an overhead mounting base **22**. That is, the mounting base **22** may be on a ceiling, defined by a cantilevered arm, etc. Height and angular orientation of the mirror **10** can be readily accomplished. While support of the mirror **10** by structure in addition to the primary support **26** is contemplated, the absence of such supplemental support simplifies the overall system and use thereof.

Further, the ability to connect and disconnect parts facilitates assembly, disassembly, and adjustment. Permanent connection of parts can be selected for safety reasons.

Once a desired viewing angle has been selected and established using the at least one holding component **94**, the connections at all ends of the rigid component(s) **58** can be firmly fixed by tightening fasteners such as the bolt **84** and nut **88** in FIG. 10.

With the structure described above, a method of suspending a mirror can be performed as shown in flow diagram form in FIG. 13.

As shown at block **120**, a body is obtained with a convex surface on which a reflective surface is located. The body is connected to a frame.

As shown at block **122**, the frame is suspended from a mounting base using at least one flexible component between the mounting base and frame such that the at least one flexible component: a) depends from the mounting base;

b) suspends the frame in an operative position below a part of the mounting base; c) is under tension from a weight of the frame; and d) provides a sole required weight support for the frame, whereby the body can be repositioned relative to the mounting base by reconfiguring the at least one flexible component.

With the frame in the operative position, the reflective surface reflects images in a vertically reflecting image range.

Optionally, as shown at block 124, the orientation of the frame may be changed to thereby change the vertically reflecting image range.

The foregoing disclosure of specific embodiments is intended to be illustrative of the broad concepts comprehended by the invention.

The invention claimed is:

1. A suspended mirror system comprising:
  - a frame;
  - a reflective surface on the frame;
  - an intermediate support;
  - a primary support configured to be connected to a mounting base so as to be in a mounting orientation wherein the primary support: (i) is configured to extend downward from a part of the mounting base; and (ii) is connected to the intermediate support;
  - at least one rigid component connecting between the frame and the intermediate support,
  - the at least one rigid component connected for pivoting movement relative to: a) the frame around only a single fixed axis; and b) the intermediate support around only a single fixed axis,
  - the frame, the intermediate support, and the at least one rigid component configured so that with the primary support in the mounting orientation an angular relationship between the frame and the intermediate support can be controllably changed so as to change and maintain an angular orientation of the reflective surface; and
  - at least one holding component connecting between the frame and at least one of: (a) the at least one rigid component; (b) the primary support; or (c) the intermediate support to stabilize the frame with the frame in a desired angular relationship with the intermediate support so that the reflective surface on the frame reflects desired images in a space within which the suspended mirror system is placed.

2. The suspended mirror system according to claim 1 wherein the reflective surface has a convex shape.

3. The suspended mirror system according to claim 1 wherein the frame comprises a substantially flat panel.

4. The suspended mirror system according to claim 3 wherein the reflective surface is defined on a body having a cup shape with an open end and the substantially flat panel is at or adjacent the open end.

5. The suspended mirror system according to claim 1 wherein the primary support comprises first and second components that with the primary support in the mounting orientation connect to the intermediate support at spaced locations.

6. The suspended mirror system according to claim 1 wherein the primary support comprises first and second components that with the primary support in the mounting orientation are configured to connect to the mounting base at spaced locations.

7. The suspended mirror system according to claim 1 wherein the intermediate support comprises an elongate bar with a length that extends substantially horizontally with the primary support in the mounting orientation, a portion of the

primary support defining an upwardly opening curved seat that receives a part of the elongate bar.

8. The suspended mirror system according to claim 7 wherein the frame comprises a substantially flat panel and the at least one rigid component is elongate and connects between the substantially flat panel and the elongate bar.

9. The suspended mirror system according to claim 8 wherein the at least one rigid component is connected to a component projecting away from the substantially flat panel for guided pivoting movement relative to the component projecting away from the substantially flat panel.

10. The suspended mirror system according to claim 1 wherein the at least one rigid component has a length and is configured so that the length of the at least one rigid component can be changed.

11. The suspended mirror system according to claim 1 wherein the at least one rigid component comprises first and second rigid components.

12. The suspended mirror system according to claim 11 wherein the first and second rigid components are each connected to the intermediate support for guided pivoting movement relative to the intermediate support around a shared axis.

13. The suspended mirror system according to claim 1 wherein the primary support in the mounting orientation has a length and comprises an elongate flexible component and is configured so that an effective length of the primary support can be selectively changed and maintained.

14. The suspended mirror system according to claim 1 wherein the primary support comprises at least three elongate flexible components.

15. The suspended mirror system according to claim 14 wherein each of the at least three elongate flexible components comprises a chain with interlocked links.

16. The suspended mirror system according to claim 14 wherein the suspended mirror system is configured so that the at least three elongate flexible components provide a sole weight support for the suspended mirror system from the mounting base with the primary support in the mounting orientation.

17. A suspended mirror system comprising:

- a frame;
- a reflective surface on the frame;
- an intermediate support;
- a primary support configured to be connected to a mounting base so as to be in a mounting orientation wherein the primary support: (i) is configured to extend downward from a part of the mounting base; and (ii) is connected to the intermediate support;
- at least one rigid component connecting between the frame and the intermediate support,
- the at least one rigid component connected for pivoting movement relative to each of the frame and the intermediate support,

the frame, the intermediate support, and the at least one rigid component configured so that with the primary support in the mounting orientation an angular relationship between the frame and the intermediate support can be controllably changed so as to change and maintain an angular orientation of the reflective surface; and

at least one holding component connecting between the frame and at least one of: (a) the at least one rigid component; (b) the primary support; or (c) the intermediate support to stabilize the frame with the frame in a desired angular relationship with the intermediate support so that the reflective surface on the frame

11

reflects desired images in a space within which the suspended mirror system is placed,
wherein the at least one holding component comprises a flexible elongate component with a length that connects between the frame and the intermediate support, the 5 flexible elongate component configured so that an effective length of the flexible elongate component between the frame and the intermediate support can be selectively changed.
